Application March 24, 1936, Serial No. 70,557
 In France April 29, 1935

4 Claims. (Cl. 250—27.5)

This invention relates to improvements in electron discharge tubes or devices and their connections.

One object of this invention is to provide new construction and mountings of electrodes in such tubes operable at short or ultra-short waves (micro-ray). The invention may also find application in other arts.

Another object of the invention is to improve the stability of the frequency characteristics of such tubes.

A further object of the invention is to supply more efficient constructions and in particular permit a greater dissipation of energy than in the previously known tubes.

In the following description it will be seen that means are provided to define the high frequency potential at one or more points of one or more electrodes of an electron discharge tube.

The invention will be understood more clearly from the following detailed description with reference to the accompanying drawing in which:

Figure 1 represents in section an improved construction of a tube employing features of this invention; and

Fig. 2 shows a side view in section of the structure of the tube of Fig. 1.

The embodiment shown in the drawing relates to a three-electrode tube of the type generally known as Barkhausen oscillators in which a so-called oscillating electrode is maintained at a continuous positive potential, while another so-called reflecting electrode is maintained at a negative potential. In such a tube it is possible, by suitable adjustment of the potentials, to obtain electrical oscillations of very high frequencies along the oscillating electrode.

In Fig. 1, the enclosing vessel of the tube is designated as 1, and 2 is the extension of the press supporting insulating members 3 and 4 in which are sealed at 5 and 6, and 7 and 8, rods 9 and 10 and 11 and 12 respectively. The rods 9 and 10 are connected at suitably chosen points of the oscillating electrode 13. To the rods 9 and 10 are fixed connections 14 and 15 serving to conduct to the outside of the tube the ultra high frequency oscillations produced along the oscillating electrode 13, or, conversely to lead to the oscillating electrode 13 ultra-high frequency oscillations produced on a receiving device connected to the conductors 14 and 15. The oscillating electrode 13 is provided at its two extremities 16 and 17 with metallic plates 18 and 19 whose electrical role will be hereinafter defined. These plates are supported by the rods 11 and 12 mentioned above.

The reflecting electrode 20 is maintained in position by a rod 21, shown in Fig. 2, serving to apply a suitable potential to this electrode 20. The extremities of the reflecting electrode also may be provided, as shown in Fig. 1, with metallic plates or flanges 22 and 23 placed substantially parallel to the flanges 18 and 19 with which the oscillating electrode is provided. The axis of this structure is constituted by a source of electrons represented here in the form of a cathode 24 in filament form, 10 maintained in position between the rod 25 and the spring 26. The heating current for the cathode is supplied through the rods 27 and 28 shown in Fig. 2.

If necessary, there may be provided inside the 15 vacuum tube a cup 29 containing a substance such as magnesium to absorb the residual gases in well-known manner.

Instead of directly including the oscillating electrode in the utilization circuit, the structure 20 which has just been described permits the coupling of the oscillating electrode as loosely as desired with the utilization circuit. This arrangement has great advantages; in particular it permits the attainment in a given oscillator tube, of 25 a considerably improved frequency stability owing to the fact that the utilization circuit reacts only slightly on the circuit which determines this frequency; and, in the case of a receiver tube, a material increase is the selectivity of the receiving 30 circuit.

In the arrangement described, the circuit determining the frequency is entirely inside the tube and is constituted by the oscillating electrode alone, means being provided to create tension 35 nodes at the extremities of this oscillating electrode. Among the means which may be employed to this end may be mentioned the addition of flanges at the ends of the oscillating electrode. These flanges cause reflections at the ends 40 of the oscillating electrode, which result in the formation at points 16 and 17 of ultra-high frequency tension nodes. In certain cases it may be well to provide also flanges 22 and 23 on the reflecting electrode, which improves the symmetry 45 of the device and assists in the dissipation of the heat generated in the system.

In this type of tube, the length of the wire of the oscillating electrode preferably should be substantially equal to the optimum wave-length 50 or in a more general manner to a multiple of this wave-length. This condition is preferable to the case in which there would be an odd number of half-waves along the oscillating electrode because it permits the coupling of the utilization circuit 55

symmetrically by the connections 9 and 10 to the oscillating electrode.

Let us take as an example the case in which the length of wire of the oscillating electrode is equal to a wave-length. The outer circuit may then be connected to the oscillating electrode by means of two parallel conductors 14 and 15, Fig. 1. The points of the oscillating electrode to which these conductors are connected are placed substantially a quarter of a wave-length away from the two extremities of the oscillating electrode. These conductors 9 and 10 pass through holes provided in the reflecting electrode 20. It is, moreover, an advantage to provide perforations in the reflecting electrode or to construct it of metal gauze so as to accelerate the removal of the heat developed in the system.

It will be noted that the addition of flanges to the extremities of the oscillating and reflecting electrodes also facilitates the dispersion of heat.

It may be noted also that the new construction of oscillating electrode described here fulfills the part of a "tank circuit" to which the utilization circuit is coupled.

In the particular example described above, it will generally be well to choose for the length of the connections 15 and 14 an odd number of quarter wave-lengths, from the electrodes of the tube to a utilization element in which a maximum current is desired.

As these connections 14 and 15 pass through the vessel 1, it is desirable to seal these connections to the vessel at points a very short distance from the axis of the structure or at a distance equal to half a wave-length so as to maintain the losses due to this sealing at as low a value as possible.

It may be noted that the negative linear conductance along the oscillating electrode is increased by the presence of the flanges 18 and 22 for the same dispersion of heat on the electrodes, the same diameter of oscillating electrode and the same operating wave-length. One of the reasons for this increase in the negative conductance is that for a particular wave-length the wire of the oscillating electrode is chosen preferably equal to this wave-length instead of a valve near 1.25 which is optimum in the case of the structure of the same type not comprising flanges at the extremities of the oscillating electrode.

A suitable potential can easily be applied to the oscillating electrode by means of a connection from a suitable source to one of the flanges of said electrode. This conductor can be brought to the outside of the tube through the base of the latter. This arrangement greatly simplifies the mounting of the tube, because all the leads (cathode, oscillating electrode and reflecting electrode) have their connections brought to the base of the tube and no loss is introduced, therefore, along the high frequency connections to the oscillating electrode.

From the point of view of the arrangement of the circuits, the tube structure shown permits considerable simplification of the connections because the tube itself carries out the separation of the high frequency circuits from the supply circuits for the filament, oscillating and reflecting electrodes and it does not require the use of a special type of base.

It is obvious that the arrangements described

have only been so described by way of example and that modifications may be made in these devices without departing from the scope of the present invention. For example, the coupling between the oscillating electrode and the transmission line terminating in a utilization apparatus may be carried out by means of either transformers or condensers. In the case of coupling by a transformer, the connections 9 and 10 will terminate in one or more turns arranged in the vicinity of or concentric to the oscillating electrode 13; in the case of coupling by capacity, for example, small condensers in series could be used in the connections 9 and 10. Other coupling devices which will appear clearly to those skilled in the art may also be employed.

Although a cylindrical symmetry tube has been described by way of example, it is clear that the invention may be applied to tubes having other kinds of symmetries, for example, to tubes provided with plane electrodes. Likewise, the elements composing the electrodes may be utilized for various purposes, for example, in ionic or electronic discharge devices. Furthermore, the invention may, of course, be applied to a tube having any number of electrodes.

What is claimed is:

1. An electron discharge device comprising an enclosing vessel a cathode within said vessel, a grid encompassing said cathode, disc members at the ends of said grid and connected thereto, supporting means for said disc members mounted within said enclosing vessel, a reflecting electrode surrounding said grid, and leading-in conductors for said grid separate from and spaced from said supporting means.

2. A Barkhausen oscillator comprising an enclosing vessel, a cathode, a grid, and a reflecting electrode, disc members at the ends of said grid and connected thereto, supporting means extending from one end of said vessel and secured to said disc members, and leading-in conductors extending from the opposite end of said vessel and connected to said grid intermediate the ends thereof.

3. An electron discharge device comprising an enclosing vessel having a stem, a cathode above said stem, a grid encompassing said cathode, disc members at the ends of said grid and connected thereto, support members extending from said stem and secured to said disc members, a cylindrical electrode surrounding said grid, support means for said electrode extending from said stem, and leading-in conductors for said grid connected thereto intermediate the ends thereof and extending from said vessel at points remote from said stem.

4. A Barkhausen oscillator comprising a linear cathode, a spiral grid surrounding said cathode and coaxial therewith, metallic disc members at the ends of said grid and at substantially right angles to said cathode, a cylindrical reflecting electrode surrounding said grid and coaxial therewith, annular flanges at the ends of said reflecting electrode disposed parallel and in juxtaposition to said disc members, and leading-in conductors for said grid secured to intermediate turns thereof, said conductors extending at substantially right angles to the longitudinal axis of said grid.
